His ATTORNEY.

UNITED STATES PATENT OFFICE.

EDWIN T. BASKIN, OF KANSAS CITY, MISSOURI.

LAUNDRY DEVICE.

1,425,828.

Specification of Letters Patent. Patented Aug. 15, 1922.

Application filed October 27, 1920. Serial No. 419,912.

To all whom it may concern:

Be it known that I, EDWIN T. BASKIN, a citizen of the United States, residing at Kansas City, in the county of Jackson and State of Missouri, have invented a certain new and useful Improvement in Laundry Devices, of which the following is a specification.

My invention relates to improvements in laundry devices.

The object of my invention is to provide a laundry device which is simple in construction, cheap to make, durable, not liable to get out of order, and with which clothes may be quickly and thoroughly cleansed and rinsed and with a minimum amount of labor.

My invention provides further a novel clothes pounder.

My invention provides still further a clothes pounder having a reversible handle and perforate body combined with novel means for bracing the handle and guarding against the clothes clogging the perforations in the body.

The novel features of my invention are hereinafter fully described and claimed.

In the accompanying drawing which illustrates the preferred embodiment of my invention,

Fig. 1 is a perspective view of my improved laundry device.

Fig. 2 is a bottom view of the clothes pounder.

Fig. 3 is a cross section on the line 3—3 of Fig. 2.

Fig. 4 and Fig. 5 are respectively plan views of the two guard members, shown detached.

Fig. 6 is a vertical sectional view of the laundry device with the body shown in a position the reverse of that shown in Figs. 1 and 3.

Fig. 7 is a plan view of a pounder embodying my improvements shown fitted in a circular clothes receptacle.

Similar reference characters designate similar parts in the different views.

Referring particularly to the first six figures, 1 designates an ordinary wash boiler of the usual oblong form.

2 designates the pounder body which is preferably of concavo-convex form and which also is preferably substantially fitted in and vertically reciprocative in the boiler

1. The body 2 is provided with openings or perforations 3 through which the water in the boiler is forced when the body is reciprocated.

Centrally mounted in the body is a vertical member comprising, preferably, a socket member 4 either end of which is adapted to receive therein the lower end of a handle 5 which may be provided with two transverse holes 6 and 7 either of which is adapted to receive therethrough a bolt 8 which is also adapted to be extended through a transverse hole provided in the socket member 4 at the outer side of the convex side of the body 2. The bolt 8 is provided with a nut 9 arranged to bear against the socket member 4 for releasably securing the bolt in its operative position in the handle and socket member.

For securely anchoring the socket member 4 to the body 2, and also for keeping the clothes from clogging the perforations 3 in the body, I provide a suitable guard which may comprise two crossed brace members 10 and 11 the ends of which are attached to the body 2 at the edge thereof. The members 10 and 11 each encircle the inner end of the socket member to which the members are attached in any suitable manner, as by soldering. The members 10 and 11 may be flat strips, as shown, each having a central hole through which the socket member is inserted.

In the operation of my invention, the body 2 is preferably first mounted in the boiler 1 with the convex side up, as shown in Fig. 1, in which position, the handle 5 is mounted in the socket member 4 with the bolt 8 in the hole 6. When the handle and body 2 are vertically reciprocated in the boiler the clothes will be compressed adjacent to the outer edges of the body and the water will be forced outwardly through the perforations 3 as the body 2 moves downwardly. By this manner of use of the pounder, with the convex side up, the clothes will be higher in the central part of the boiler. The handle 5 may then be removed from the socket member 4 and inserted into the other end of the socket member 4, as shown in Fig. 6, the bolt 8 being placed in the hole 7 of the handle. The body 2 will now be reversed in position with respect to the handle 5. The body 2 is then, while in this reverse position, inserted into the boiler 1 and reciprocated by means of

the handle 5. The convex side of the body 2 being now on the under side and next to the clothes, the reciprocation of the body 2 will compress the central portion of the 5 clothes, and the water will be forced inwardly through the perforations 3.

By so operating the pounder, the clothes may be easily, quickly and thoroughly cleansed.

10 The invention is also adapted for use with a circular clothes receptacle, such as a tub 12, Fig. 7, in which case the body of the pounder, designated by 13 is circular in plan and substantially slidably fitted to the inner 15 wall of the tub. In other respects the pounder is the same as described with reference to the form shown in the other figures, both in construction and mode of operation.

20 I do not limit my invention to the struc-

tures shown and described, as many modifications, within the scope of the appended claim, may be made without departing from the spirit of my invention.

What I claim is:—

In a laundry device, a clothes pounder having a perforate concavo-convex body, a socket member attached at one end to said body, a guard attached to the body and extending across the concave side of the body 30 and attached to and serving as a brace for the other end of the socket member, and a handle adapted to be inserted into either end of the socket member and having means for being releasably attached to the socket 35 member, substantially as set forth.

In testimony whereof I have signed my name to this specification.

25

EDWIN T. BASKIN.
